UNITED STATES PATENT OFFICE.

RACHEL BARBOUR, OF SEYMOUR, INDIANA.

COMBINATION PORCH-SWING AND CRIB.

1,379,956.

Specification of Letters Patent. Patented May 31, 1921.

Application filed January 21, 1921. Serial No. 438,903.

To all whom it may concern:

Be it known that I, RACHEL BARBOUR, a citizen of the United States, residing at Seymour, in the county of Jackson and State of Indiana, have invented certain new and useful Improvements in Combination Porch-Swings and Cribs, of which the following is a specification.

The object of this invention is to provide 10 a porch swing with means for converting a portion thereof into a crib in which an infant may be placed and protected, while the other part of the swing may be used for other purposes.

15 A further object of the invention is to provide means for this purpose which may be easily applied to swings of various kinds and sizes, and which when not needed for use may be detached from the swing and 20 folded or rolled so as to occupy only a small space for transportation or storage.

According to my invention the crib attachment is constructed of two end parts and an extensible and collapsible side which 25 connects the ends of the crib and which is so constructed that the crib member may be given any desired length. Preferably the side consists of lazy-tongs which may be very easily extensible and collapsible and 30 which at the same time are strong and provide desirable ventilation. The ends and the side are provided with fastening devices which are adapted to engage corresponding fastening devices on the swing.

35 In the accompanying drawings:—

Figure 1 is a perspective view of a combination swing and crib embodying my improvements.

Fig. 2 shows a transverse section thereof.

40 Fig. 3 is a perspective view of the crib member detached and partially folded.

Fig. 4 is a detail view showing the manner of connecting the lazy-tongs to the posts.

The porch swing A is of well known construction, being of sofa or settee style suspended by chains B. The crib member comprises ends C and D and a collapsible and extensible side E. Each end member consists of two posts c, c' or d, d' connected by 45 canvas or other suitable material F or F'. The side E consists of lazy-tongs, the ends of the lazy-tongs being pivotally connected with the posts c and d near their upper and lower ends.

55 As shown in Fig. 4, the ends of the lazy-tongs are so connected with the posts that they have freedom of movement when open-

ing and closing. For this purpose the end bars x of the lazy-tongs may be pivoted at y to arms z extending through slots in the 60 posts, said arms being pivotally connected with the posts as shown.

The crib member is shown separately in Fig. 3 and as will be observed it may be folded into a small space for transportation 65 or storage. Fig. 3 shows the member only partially folded.

Suitable fastening devices are employed for attaching the crib to the swing. Preferably I use hooks g on the post d adapted to 70 engage eyes h on a front corner post of the swing and hooks i on the post d' adapted to engage eyes k on a rear corner post of the swing. The post c' of the opposite end member is provided with hooks l adapted to 75 engage eyes m on the back of the swing. The post c has a hook n adapted to engage an eye n' on the front bottom rail of the swing. The length of the crib may be varied at will to accommodate a mattress or cushion 80 M of any desired length. An infant may be placed in the crib when the latter is mounted and secured in the manner indicated in Fig. 1, while the nurse or mother can be seated on that portion of the swing not occupied by the crib. When not needed for 85 use, the fastening devices may be detached and the crib member may be folded and stored in the manner before described.

Fastening devices o may also be provided 90 where indicated to secure the side member to the front bottom rail of the swing.

While I have shown my improvements applied to a porch swing, it is obvious that they may be applied to other articles of furniture of a similar nature.

I claim as my invention:

1. A crib member attachment for swings, comprising ends, each consisting of posts and a connecting flexible member, and a side 100 member connecting the end members consisting of lazy-tongs.

2. The combination with a swing of a crib member attachment therefor, comprising end members consisting of posts connected by flexible material and lazy-tongs connecting the end members on one side and fastening devices carried by the posts of the end members for attaching the crib member to the swing.

In testimony whereof, I have hereunto 110 subscribed my name.

RACHEL BARBOUR.
